Rush B. Hout and Casimir V. Ufnal,
Cherry Creek, N. Y.

Application January 15, 1949, Serial No. 248

Term of patent 3½ years

(Cl. D44—29)

To all whom it may concern:

Be it known that we, Rush B. Hout and Casimir V. Ufnal, citizens of the United States, residing at Cherry Creek, in the county of Chautauqua and State of New York, have invented a new, original, and ornamental Design for an Enclosed Knife Holder, of which the following is a specification, reference being had to the accompanying drawing, forming part thereof.

Fig. 1 is a front elevational view of an enclosed knife holder, showing our new design;

Fig. 2 is a side elevational view; and

Fig. 3 is a top plan view thereof.

We claim:

The ornamental design for an enclosed knife holder, substantially as shown.

RUSH B. HOUT.
CASIMIR V. UFNAL.
